UNITED STATES PATENT OFFICE.

RICHARD F. DOWNEY, OF MILWAUKEE, WISCONSIN, ASSIGNOR TO HUGO LOEWEN-BACH, OF MILWAUKEE, WISCONSIN.

BOWLING GAME.

1,160,151.

Specification of Letters Patent. Patented Nov. 16, 1915.

Application filed February 1, 1915. Serial No. 5,356.

To all whom it may concern:

Be it known that I, RICHARD F. DOWNEY, a citizen of the United States, and resident of Milwaukee, in the county of Milwaukee and State of Wisconsin, have invented certain new and useful Improvements in Bowling Games; and I do hereby declare that the following is a full, clear, and exact description thereof.

10 My invention refers to bowling games and has for its object to provide a simple, economical and effective game apparatus of the above described character.

The construction and arrangement of my improved apparatus is such that the pins are knocked down from a board upon which they are grouped, by a trolley-carried ball which is suspended overhead and adapted to strike the pins as it travels from the point 20 of play over the board in place of the ordinary manner, whereby a ball is rolled upon an alley.

Specific objects of my invention are to provide an overhead trolley mechanism for suspending the ball; to provide a flexible trolley rail which is slightly inclined upwardly from the point of play toward the group of pins, whereby said trolley will be returned to the player automatically; to provide means whereby the ball, after striking and passing through the pins, is returned outside the field of standing pins, whereby such standing pins will not be knocked down upon the recovery stroke of the ball as it travels back to the player; to provide any form of token-controlled means for locking and releasing a manually operated pin set-up mechanism, after a predetermined number of plays; to provide means for locking the trolley-supported ball after a predetermined number of plays, whereby the trolley-carried ball is held in one position to prevent it being shifted back and forth upon the trolley except when the apparatus is entirely released and set for play.

With the above and other objects in view the invention consists in certain peculiarities of construction and combination of mechanical elements as set forth hereinafter 50 with reference to the accompanying drawings and subsequently claimed.

In the drawings Figure 1 represents a diagrammatic elevation of a bowling apparatus embodying the features of my invention, 55 parts being broken away and in section to

more clearly illustrate various details of construction; Fig. 2, a detailed view of the rear end of the cable showing the trolley mechanism in its locked position with the pin ball lifted; Fig. 3, a detailed elevation 60 of a mechanism for locking and releasing the pin set-up mechanism; Fig. 4, a detailed section of the same, the section being indicated by line 4-4 of Fig. 3, and Fig. 5, a detailed cross-section, as indicated by line 5-5 of Fig. 1.

Referring by characters to the drawings, 1 represents the ground line upon which rests a boxed pin board 2 arranged to receive the usual arbitrarily arranged group 70 of pins 3, each of which pins is connected to a cross-head 4 by a flexible cord or runner 4' that passes through an aperture centrally disposed with relation to its companion standing pin, to the bottom of which pin the runner 4' is attached. Hence it will be seen that from front to rear the runners 75 are of unequal lengths, whereby when the cross-head is drawn toward the operator a full stroke, all runners are rendered taut 80 to thus cause the connected pins to assume an upright position in alignment over their respective board apertures. The cross-head 4 is mounted within the boxed pin board and provided with suitable guides 5, through 85 which a stem 6 of the cross-head is adapted to slide. Interposed between one of the guides 5 and a collar 6' that is fast on the stem, is a coiled spring 7, the expansive force of which coiled spring tends to draw the cross-head toward the rear of the pin-board, whereby all of the runners 4' are slackened when the pin setting-up device is 90 in its normal position of rest. A flexible runner in the form of a cable 8 is connected to the cross-head 4 and a lever 8' that is positioned at a distant point from the pin board, at which point the game is played. The rear end of the stem 6 carries a pull 95 pawl 9, which pawl engages the teeth of a ratchet-wheel 10 that is mounted upon a suitable shaft 10', the same being provided with journals, not shown, which journals are suitably affixed to the walls of the box-like pin-board. In this exemplification of my 100 invention the ratchet-wheel is provided with twelve teeth and thus it is manifest that after the set-up mechanism has been manipulated eleven times, the wheel will have made a complete revolution.

105

110

In order to lock the set-up mechanism after eleven manual operations, I provide the ratchet-wheel 10 with a stop-lug 11, which stop-lug is engaged by a pivoted locking tumbler 12. The engaging nose of the locking tumbler in this exemplification of my invention, constitutes a spring-controlled oscillatory jaw 12', which jaw is pivoted to the free end of the tumbler proper and its movement in either direction is limited by stop pins 13, 13'. Thus it will be seen that when the parts are in the position shown in Fig. 3, the nose or jaw portion of the tumbler is in abutting engagement with the stop-lug 11, whereby the wheel is locked against rotation, which rotation is imparted thereto through the pull-pawl 9 by a manual operation of the lever 8'.

In order to release the locked wheel 10, I provide a magnet 14, which magnet is adapted to exert influence upon the tumbler 12, the said tumbler forming an armature for the magnet. The magnet is interposed within an electrical circuit *a*, that is interrupted by terminal conductors *b*, *b'*, which terminal conductors may constitute part of a token-receiving box located conveniently at the point of play, as shown.

From the foregoing description it is manifest that when a coin *c* is caused to travel over the conductor members *b* and *b'*, it will close the gap therebetween and thus close the circuit, whereby the magnet is energized to cause the tumbler 12 to be momentarily lifted. The momentary lift of the tumbler will thus draw the jaw 12' clear of the stop-lug 11, whereby the spring pressure of said jaw will cause the same to shift over the stop-lug and thus rest thereon, preventing the return of the tumbler to its normal position. The player or operator, who is located near the operating lever 8', can now manipulate said lever, whereby the wheel is rotated one tooth in the direction of the arrow and coincident to this movement the runner-connected group of pins will be drawn to their vertical set positions with relation to the pin-board and, upon release of the lever 8' after a full stroke to effect the desired set, the spring 7 will cause the cross-head and stem to return to their normal positions of rest, as shown in Fig. 1, thus slackening all of the runners and placing the push-pawl 9 in a position with relation to the ratchet wheel for a repeat operation.

The game is played by the operator from the distant point mentioned by manipulating a bowling ball 15, which bowling ball is suspended by a cord or runner 15' from a suitable trolley mechanism A. The trolley mechanism comprises a carriage 16 carrying front and rear wheels 16', which wheels are mounted upon a flexible track in the form of a cable 17 that is yieldably connected at each end to fixed points 17', by interposed coiled

springs 17", as shown in the diagram. The flexible track 17 is slightly inclined from the point of play upwardly toward the pin board and positioned centrally over the same.

In order to clear the ball from inadvertently striking any upstanding pins upon the return movement of said ball after a play, I provide a shifting means, which shifting means is adapted to automatically lift the ball at the end of its play stroke above the pins. With this object in view the carriage 16 of the trolley has pivotally mounted thereon a spring-controlled lock and release mechanism comprising a lifting arm 18, to the end of which is attached the ball suspending runner 15'. A coiled spring 18' connects this arm with the carriage, which coiled spring is of sufficient strength to overcome the weight of the bowling ball 15. Before the bowling ball is manipulated in a play, it is drawn downwardly by the operator, whereby the coiled spring 18' is loaded and the arm 18 is locked in this loaded position by a lock and release trigger 19, which trigger is pivoted to a forward extension of the carriage and is provided at its lower free end with a notch 19' for engagement with a pin 20 that constitutes part of the arm 18. The trigger 19 terminates with an upwardly projecting trip finger 19", which trip finger is adapted to contact with a fixed member 21 in the form of a cable that is positioned transversely of the track 17 at a point near the rear end of the group of pins, whereby said trip finger is released after the bowling ball has completed its play stroke. After completing said play stroke the ball is arrested by coming in contact with a flexible buffer-shield 22, which buffer-shield forms no part of my invention, being suitably suspended by stay-rods 22' from the pin-board, as shown. It is also desirable, after a predetermined number of plays, to lock the trolley mechanism in order to prevent the same from being tampered with when not in use and to accomplish the desired result I have shown a carriage locking lever 23, which lever is pivoted overhead in any suitable manner and formed with a spear-head locking nose 23' at its free end. The locking nose is normally held in suspension by the weighted end 23" of the lever and said nose is so positioned as to engage a corresponding head 24, which locking head projects from the trolley carriage 16.

Flexibly connected to the lever 23 by a cable 24 is a plunger rod 25, the cable being passed over a guide pulley 24', whereby its direction is changed to form a connection at the tail of the thrust rod 25. The thrust rod 25 is slidably mounted in suitable bearings within the box portion of the pin board 2 and the inner end of said thrust rod is ar-

ranged in the path of travel of the ratchet-wheel stop-lug 11, the said end of the thrust-rod being terminated at a point adjacent to the jaw 12' of the tumbler 12. By 5 this arrangement when the ratchet-wheel 10 has completed its cycle of operation, the stop-lug in describing its last movement, equal to the space between the teeth of the ratchet, will engage the end of the protruding thrust-rod 25 and force the same backward. The backward movement of the thrust-rod, owing to its yieldable cable connection with the lever 23, will thus cause the nose 23' of this lever to be depressed into 10 the position for engagement with the locking head 24 of the trolley carriage. Hence when the operator, by a throwing movement, causes the pin ball to effect its last play stroke, when said stroke is completed 15 the head 24 and lever nose 23' will be lockingly engaged, whereby the trolley is held in suspension at the terminal of its last stroke. It is also manifest that after each 20 play movement of the ball, the trip finger will be engaged by the cross-member 21 to thus release the spring-tensioned lifting-arm 18, whereby the ball 15 will be raised to an elevation above the heads of the pins and thus when said ball travels back to the 25 point of play, due to the inclination of the track 17, it will clear all standing pins. This device renders it possible to play the game in the ordinary manner and the ball can be again returned for the purpose of 30 displacing any standing pins after the first roll or play. It should be understood that, owing to the flexure of the suspension and carrying means of the pin ball, considerable science and skill can be displayed in a play, 35 as, for example, the ball may be aimed to strike any selected pin by deflecting said ball from its normal straight course. In this exemplification of my invention, after eleven strokes of the pin ball, the mechanism 40 will all become locked and in order to renew the play a token must be dropped into the box at the point of play, whereby the magnet circuit is closed to cause energization of the said magnet to lift the releasing tumbler 12. The ratchet-teeth upon the 45 face of the wheel or disk 10 can be varied indefinitely, whereby the play may be restricted or increased in accordance therewith for a single token.

50 In order to automatically load the spring 18' which controls movement of the ball-carrying arm 18, I provide a tappet 26, which tappet is fixed to the anchor-post B that carries the runner or cable 17. The arm 55 18 is provided with a tail-piece 18'', which tail-piece is adapted to engage the tappet when the trolley recedes to the distant point for play and thus cams the arm 18 downwardly whereby it is locked in its loaded position, as shown in Fig. 1. Thus it will be

observed that this automatic means will set the mechanism for play, whereby the parts are ready for the operator when the trolley travels back to the distant point for operation.

70 Referring to Fig. 1, attention is called to the fact that the trigger arm 19 is provided with a locking nose 20' for engagement with the pin 20 of the ball-carrying arm, whereby said arm is locked in its upward position 75 when elevated by the coiled spring 18'. Thus the ball-lifting arm is held against vibration when in its elevated position. Owing to this locking engagement between the trigger and ball-lifting arm 18, it is 80 necessary to effect a release of the same prior to the arm 18 being automatically forced down to the position shown in Fig. 1 by the mechanism previously described. This release is effected by a tongue member 26', 85 which extends from the tappet member 26. Hence it will be seen that when the trolley returns to its position of play the arm 19 will frictionally engage the tongue 26', whereby said arm will rock backward in opposition to its light-retaining spring. Thus the pin 20 will be freed from the nose 20' just prior to engagement of the tail 18' with the trigger 26, whereby the arm 18 is forced 90 downwardly. The pin 20 is locked in connection with the nose portion 19' of the trigger arm 19 due to the fact that the spring which controls the trigger 19 is now free to work owing to the fact that the tongue 26 at this point is provided with an 95 offset, as shown in Fig. 5, to permit said action. It is obvious that I may, in some instances, dispense with the automatic mechanism for lowering the ball 15, in which case the same can be locked by a simple pull 100 down in opposition to the coiled spring 18' after the pin 20 has been freed from the notch 20' of the trigger arm 19.

105 In order to prevent the trolley from returning immediately after a play stroke to the point of play due to the inclination of the trolley-wire 17, I provide a spring clip 110 27, which clip is secured to the post just rearward of the pin and board. The spring jaws of the clip 27 are arranged to engage a 115 head 28 that projects from the trolley carriage, the said head entering between the jaws, whereby it is firmly gripped in a position to be locked by the locking head 24.

120 In order to free the trolley mechanism from the spring clip 27 after each play, I provide a release cable 28, which cable is held in the form of a loop over the pin board by a weighted cable connection 28'. One end of the cable 28 is guided over a pulley 125 29 at the play end of the apparatus and terminates with a handle 29', as shown, it being understood that the cable stretch 28' is also suitably guided over a sheave 28''. By this arrangement it will be observed 130

that when the trolley has come to rest at the rear end of the apparatus, a spur 24' of the head 24 will engage the looped portion of the cable 28 and hence, when it is desired to 5 free the trolley, the operator draws upon the cable 28, whereby movement of said cable due to its engagement with the spur 24', will cause the trolley to be forcibly disconnected from its engagement with the spring-clip 10 27 and after the trolley is freed it is obvious that it will, by gravity, travel to the position shown in Fig. 1.

While I have shown and described mechanism in detail for carrying out my invention, it is manifest that such details may be 15 varied within the knowledge of skilled mechanics without departing from the spirit of said invention.

I claim:

20 1. In a bowling game having a pin board, pins adapted to be arbitrarily grouped thereon, mechanical means for grouping the pins in their set positions upon the board, an overhead flexible track, and a ball-carrying trolley mounted upon the track; the combination of a ball-lifting mechanism carried by the trolley, a ball-suspending means carried thereby, a lock and release trigger mechanism for the ball-lifting 25 means, and a trigger-releasing means positioned over the pin board.

2. In a bowling game having a pin board, pins adapted to be arbitrarily grouped thereon, mechanical means for grouping the pins in their set positions upon the board, an overhead flexible track, and a ball-carrying trolley mounted upon the track; the combination of a spring-controlled ball-lifting arm carried by the trolley, a ball-suspending means therefor, a lock and release trigger mechanism for the ball-lifting 30 means, and a trigger-releasing means positioned over the pin board.

3. In a bowling game having a pin board, pins adapted to be arbitrarily grouped thereon, mechanical means for grouping the pins in their set positions upon the board, an overhead flexible track, and a ball-carrying trolley mounted upon the track; the combination of a ball-lifting arm carried by the trolley, a ball suspended therefrom, means carried by the arm for overbalancing 35 the weight of the ball, a pivoted lock and release trigger for engagement with the arm whereby said arm is held against movement 40 during a play stroke of the ball, and a fixed member positioned over and rearwardly of

the pin board for engagement with the trigger.

4. In a bowling game having a pin board, 60 pins adapted to be arbitrarily set up thereon, an overhead track, and a trolley-supported ball suspended from the track; the combination of shifting mechanism for causing the suspended ball upon its return stroke 65 to travel outside the field of the standing group of pins.

5. In a bowling game having a pin board, pins adapted to be arbitrarily grouped thereon, mechanical means for grouping the 70 pins in their set positions upon the board, an overhead flexible track, a ball-carrying trolley mounted upon the track; and a pin ball suspended from the trolley; the combination of mechanism for locking the 75 mechanically operated pin-grouping means, and mechanism associated with said locking mechanism for locking the trolley at the end of the play stroke of the ball.

6. A bowling game comprising an apertured pin board, a reciprocative pin set mechanism mounted under the pin board, flexible runners connecting the pin setting mechanism and extending through the board apertures, pins carried thereby, electrically 85 controlled locking mechanism for the pin-setting mechanism, an overhead track, a ball-carrying trolley mounted thereon, and means associated with the electrically controlled pin set-up locking mechanism for locking 90 the trolley with relation to movement thereof upon the track.

7. In a bowling game having a pin board, pins adapted to be arbitrarily grouped thereon, mechanical means for grouping the 95 pins in their set positions upon the board, an overhead track, and a ball-carrying trolley mounted upon the track; the combination of a spring-controlled arm, a ball flexibly secured thereto, means for locking the 100 arm whereby the ball is held at a low elevation, means for moving the arm to its locking position, and a trip means for the locking mechanism positioned over the pin board.

In testimony that I claim the foregoing I have hereunto set my hand at Milwaukee in the county of Milwaukee and State of Wisconsin in the presence of two witnesses.
